UNITED STATES PATENT OFFICE.

ALFRED E. KAISER, OF SEATTLE, WASHINGTON, ASSIGNOR TO SPECIALTY MANUFACTURING COMPANY, OF SEATTLE, WASHINGTON, A CORPORATION OF WASHINGTON.

PHOTOGRAPHIC-PRINTING MACHINE.

1,350,256

Specification of Letters Patent. Patented Aug. 17, 1920.

Application filed November 19, 1917, Serial No. 202,868. Renewed June 28, 1920. Serial No. 392,513.

To all whom it may concern:

Be it known that I, ALFRED E. KAISER, citizen of the United States, residing at Seattle, in the county of King and State 5 of Washington, have invented a certain new and useful Improvement in Photographic-Printing Machines, of which the following is a specification.

My invention relates to improvements in 10 photographic printing machines, and the object of my invention is to provide a photographic printing machine which shall be adapted for use in the operation of printing on sensitized sheet material photographic 15 pictures from negatives of such pictures, and which shall embody operative clamping means for quickly clamping a negative with an even pressure between the surface of the sensitized sheet, upon which the picture is 20 to be printed, and the flat surface of one side of a transparent plate whose other side may be exposed to rays of light of an associated lamp, without wrinkling either said negative or said sensitized sheet material. 25 I accomplish this object by devices illustrated in the accompanying drawings wherein—

Figure 1 is a plan view of a photographic printing machine embodying my invention 30 as it appears when a sensitized sheet is clamped in a position to be printed;

Fig. 2 is a view of the same in vertical cross-section on broken line 2, 2 of Fig. 1, as it appears when some of its parts are in 35 positions that will permit the disposal of a sensitized sheet in one of its operative positions;

Fig. 3 is an enlarged fragmentary view of the same in vertical cross-section on 40 broken line 3, 3 of Fig. 7;

Fig. 4 is an enlarged fragmentary view of the same in vertical cross-section on broken line 4, 4 of Fig. 7;

Fig. 5 is a view of the underside of a 45 movable part of the same;

Fig. 6 is a view of said movable part of the same in longitudinal section on broken line 6, 6 of Fig. 5;

Fig. 7 is a plan view of the same with said 50 movable part removed;

Fig. 8 is a fragmentary view of the same in vertical cross-section on broken line 8, 8 of Fig. 7; and

Fig. 9 is a perspective view of details of the same.

Referring to the drawings, throughout which like reference numerals indicate like parts, a table board 10 is disposed to serve as a greater portion of the top wall of a box whose rearward vertical wall 11 is 60 shown in Figs. 1 and 7 by full lines and the top edges of the outer side of whose vertical side walls 12 and 13 are indicated partly by full lines, and partly by broken lines in said Figs. 1 and 7, and the top edge of the 65 outer side of whose front wall 14 is indicated by a broken line in said Figs. 1 and 7, said rearward wall 11, front wall 14 and the side wall 13 being more clearly shown in Fig. 2.

The rearward vertical wall 11 projects upwardly higher than the top ends of the side walls 12 and 13 and the front wall 14, as shown more clearly in Fig. 2, and the two opposite end edge portions and the 75 front edge portion of the table board 10 all extend outwardly beyond the outer edges of the ends of the side walls 12 and 13 and the outer edge of the front wall 14, as indicated in Figs. 1 and 7.

Disposed between the rearward wall 11 and the inner edge of the table board 10 is a thinner and narrower board 15 which extends between the outer edges of the vertical side walls 12 and 13 to serve as a lesser 85 portion of the top wall of said box.

As shown more clearly in Figs. 2 and 7 the table board 10 is provided with a rectangular opening 16 extending downwardly therethrough, the side and end surfaces of 90 the walls of said opening 16 being provided each with a narrow cleat 17 that is spaced from the top surface of the table board 10 for a distance equal to the thickness of a glass plate 18 which is removably disposed 95 to rest on the top surface of said cleats 17, whereby the top surface of said glass plate 18 registers with the top surface of the table board 19.

Adjacent to the rearward edge of the 100

glass plate 18 and nearer the left hand edge thereof, as indicated in Fig. 7, a rectangular portion 19 of the area of said glass plate is clearly transparent while the bottom surface of the entire remaining portion of the area thereof is made to be opaque by the means of a coating of black paint through which rays of light cannot pass.

The dimensions of the transparent area of the glass plate 18 is made to be equal to the dimensions of the photographic picture which is to be printed on a sheet of sensitized photographic paper.

Between the rearward edge of the opening 16 and the board 15 a portion of the table board 10 is excavated to form a rectangular recess within which is disposed a separate board 20 that fits therein.

The top surface of said board 20 is provided with a recess 21 that extends throughout its length, the form of which recess 21 in cross-section is shown in Figs. 2, 3 and 4.

A larger rearward portion of the board 20 and a larger rearward portion of the recess 21 is covered by a plate 22 of thin sheet metal of the form in area shown in Fig. 7.

The smaller forward portion of the recess 21 and the forward top portion of the board 20 is covered by a plate 23, of thin sheet metal, of the form and area shown in Fig. 7, said plate 23 being riveted to the front end portion of a lever 24 which is fulcrumed by a V-shaped portion 25 in a depression formed in the bottom of the recess 21, as shown in Fig. 3, the rearward end of said lever 24 being provided with a button 26 which is disposed to project upwardly through the rearward portion of the plate 22, whereby a depression of said button 26 will raise the plate 23, thus to permit the rearward edge portion of a photographic negative, not shown, to be disposed to be clamped to the top surface of the glass plate 18 over the rearward edge portion of which projects spaced parts 27, 28, 29 and 30 of the plate 23 as shown in Fig. 7.

To the under side of the plate 23 is also riveted the front end portions of two flat springs 31 and 32 whose rearward end portions are fastened to the top surface of the rearward portion of the board 20, as indicated in Fig. 4, which flat springs 31 and 32 serve as spring hinges that tend normally to press the plate 23 forcibly downward to cause its spaced parts 27, 28, 29 and 30 to clamp said photographic negative in its correct position on the glass plate 18.

Hinged by hinges 33 and 34 to the rearward portion of the table board 10 is a platen board 35 which is adapted to swing between its position, shown in Fig. 2, and its position, shown in Fig. 1, in which latter position it may press a piece of sensitized photographic paper, not shown, evenly on to a photographic negative, not shown,

that is clamped by the spaced parts 27, 28, 29 and 30 in its proper position over the transparent portion 4 of the glass plate 18.

Like the hinge 34 shown in Fig. 8, both the hinges 33 and 34 are made to be yielding by reason of the fastening screw 36 not being screwed into the table board 10 to its fullest extent, whereby the platen board 35 may find an even seat on the top surface of said table board 10 and glass plate 18.

The engaging side of the platen board 35 is covered with one piece of soft textile fabric 37 throughout its whole area, and throughout that portion of its area which engages with the entire area of the glass plate 18 another piece of like soft textile fabric 38 is adhered to the fabric 37 thereby to provide a soft engaging surface with which to press against a piece of sensitized photographic paper to clamp said paper on to a negative disposed on the glass plate 18.

Adjacent to the inner side surface of the fabric 37, the platen board 35 is provided with two recesses 39 and 40 indicated in Fig. 6, which extend in a transverse direction to intersect a longitudinal slot 41 that extends through the platen board 35 to the outer side thereof throughout a distance equal to the lengths of the plates 22 and 23 and in a position registering with said plates 22 and 23.

Extending from the left hand end of said slot 41 at a right angle therefrom, in a direction toward the front edge of said platen board 35, is a slotted groove 42, as indicated in Fig. 6.

The fabrics 37 and 38 over the slots 41 and 42 are provided with a slit, and freely disposed in said slots 41 and 42 is an angular clamping member of the form shown by an enlarged perspective view in Fig. 9, made of thin sheet metal, the longer and wider portion 43 being disposed to project through the slot 41 to a distance therefrom and to the outwardly projecting edge portion of said portion 43 is fastened a wooden strip 44 of semi-circular cross-section against which one may press to move the clamping member inwardly in opposition to two flat springs 45 and 46, like ends of which project into oblong holes 47 and 48, respectively, which extend through said longer and wider portion 43, the other ends of said flat springs 45 and 46 being fastened near the rearward edge of the platen board 35, as indicated in Fig. 2, said springs normally maintaining said clamping member in a position where the wooden strip 44 is farthest from the outer surface of the platen board 35.

The shorter and narrower portion 49 of the clamping member, on its edge, is provided with an integral flange 50 that aids to limit the outward movement of said clamping member, while the inner edge of

the longer and wider portion 43 is provided with integral spaced clamping tongues 51, 52, and 53 which extend at right angles therefrom, as shown in Figs. 2 and 9, which 5 clamping tongues serve to clamp a piece of sensitized photographic paper, not shown, against the surface of the fabric 38 in a position to adapt it to engage with a negative disposed on the transparent portion of the 10 glass plate 18, in response to the action of the flat springs 45 and 46.

The tongues 51, 52 and 53 are narrower than the spaces between the spaced parts 27 and 28, the spaced parts 28 and 29 and 15 between the spaced parts 29 and 30 respectively, and said tongues 51, 52 and 53 are so respectively disposed that when the platen board 35 is swung downwardly into its position as shown in Fig. 1 then they fall 20 into respective spaces thereby slightly crimping the edge portion of the sensitized paper, not shown, firmly to hold it in its proper position on the negative, not shown, that is disposed on the transparent portion 25 of the glass plate 18, said sensitized paper being at the same time pressed against said glass plate 18 by fabric 28 in an obvious manner.

Extending obliquely downward from the 30 top of the rearward wall 11 to the board 15, as shown more clearly in Fig. 2 is a bumper board 54 against which the wooden strip 44 may rest when the platen board 35 is in the position shown in Fig. 2 thus to press 35 inwardly the clamping member to disengage its tongues 51, 52 and 53 from the fabric 38 thereby to permit the insertion of a piece of sensitized photographic paper that is to be printed.

40 Within the box formed by the vertical walls 11, 12, 13 and 14 is placed an electric lamp, not shown, whose rays of light may project upwardly through the transparent portion of the glass plate 18, and through 45 any negative that may be placed thereon, to impinge on a piece of sensitized paper disposed on said negative thereby to print the picture of said negative on said sensitized paper in a well known manner.

50 To utilize a photographic printing machine that embodies my invention in the manner illustrated and described, the platen board 35 is disposed as shown in Fig. 2, whereupon the button 26 is depressed to 55 raise the plate 23, then a negative is disposed on the transparent portion of the glass plate 18 with its rearward edge portion under the spaced parts 27, 28, 29 and 30, and thereupon the button 26 is released to permit 60 said spaced parts 27, 28, 29 and 30 to clamp said negative in its proper position on said glass plate 18.

The negative being properly disposed then a piece of sensitized paper to be printed 65 is disposed on the fabric 38 with one of its

edge portions under the clamping tongues 51, 52 and 53 whereupon the platen board is swung forwardly and downwardly to its position shown in Fig. 1, which act will cause the flat springs 45 and 46 to press said 70 tongues 51, 52 and 53 against said edge portion of said sensitized paper to hold it in its proper position against the fabric 38 to dispose said paper in its position over the transparent portion of the glass plate 18 75 where it is allowed to remain long enough for rays of light from the lamp in the box to print the picture that is photographed on the negative, after which the platen board is again disposed in its position shown in 80 Fig. 2 to permit the removal of the now printed sensitized paper, whereupon the same operation may be repeated.

Obviously, for negatives of different dimensions, glass plates of the same size but 85 having transparent portions of proper different dimensions may be substituted for the glass plate 18, and changes may be made in the forms, dimensions and arrangement of parts of my invention without departing 90 from the spirit thereof.

What I claim is:

1. A photograph printing machine of the class described, which embodies a lamp box; a table board disposed to serve as a top wall 95 of said lamp box; said table board being provided with an opening extending downwardly therethrough to the interior of said lamp box; a transparent plate removably disposed within said hole with its top surface registering with the top surface of said table board; means for releasably clamping a photographic negative on said transparent plate; a platen board hinged to an edge portion of said table board and adapted to be 100 swung on its hinges to engage and disengage the top surface of said table board evenly to press a sensitized photographic paper against a negative disposed on said transparent plate, said platen board being provided with a slot extending therethrough from its engaging side to its other side; a clamping member freely disposed to extend through said slot and provided with integral clamping means operatively disposed to be adapted to clamp an edge portion of sensitized photographic paper in a required position against the engaging surface of said platen board; resilient means associated with said platen board and with said clamping member, and operatively disposed to press said clamping member in a direction to cause said clamping means to clamp said paper against the engaging side of said platen board; and a fixed bumper associated with said table, 110 and disposed operatively to be engaged with that portion of said clamping member that projects from said other side of said platen board to release said clamping member in opposition to the force of said resilient 115 means.

- means and in response to the act of swinging said platen board upwardly and backwardly away from the transparent plate and negative.
5. 2. In a device of the class described, the combination with an apertured support having a transparent plate in the aperture thereof and means to clamp a photographic negative on said plate of a platen board hinged to said support and having a spring pressed means to normally clamp a sheet of sensitized paper against the engaging face thereof, and a bumper carried by the support engageable by the paper clamping means when the platen is swung to an inoperative position away from the transparent plate and negative to automatically release said paper clamping means from the paper and the paper from the platen board.
10. 3. In a device of the class described, the combination with an apertured support having a transparent plate in the aperture thereof and means to clamp a photographic negative on said plate, of a platen board hinged to an edge of said support and having a slot extending therethrough from its engaging side to its other side, a clamping member freely disposed to extend through said slot and provided with integral clamping means 25 operatively disposed to clamp an edge portion of sensitized photographic paper in position against the engaging face of said platen board, a resilient means associated with said platen board and with said clamping member and disposed to press said clamping member in a direction to cause the same to clamp the paper against the engaging side of the platen board, and a fixed bumper associated with said support and 30 disposed to be engaged by that portion of the clamping member that projects from said other side of said platen board to move said clamping member in opposition to the force of said resilient means and thereby au-
- tomatically release the clamping means from the paper and the paper from the platen board when the latter is swung to an inoperative position away from the transparent plate and negative.
4. In a device of the class described, the combination with an apertured support having a transparent plate in the aperture thereof and means to clamp a photographic negative on said plate, of a platen board hinged to said support and having a spring pressed means to normally clamp a sheet of sensitized paper against the engaging face thereof, and a bumper carried by the support engageable by the paper clamping means when the latter is swung to an inoperative position away from the transparent plate and negative to automatically release said paper clamping means from the paper and the paper from the platen board, said paper clamping means affording a support for the paper at all times when the platen board is moving from operative to inoperative position.
5. In a photographic printing machine, a lamp box closed on one side by a transparent plate, means including a plate having spaced edge parts to clamp a negative on said transparent plate, a platen board movable toward and away from said transparent plate, and means including clamping member to clamp a sheet of sensitized paper against the engaging face of said platen board, said clamping member having spaced clamping tongues arranged to fall into the spaces between the spaced edge parts of the first named clamping plate and thereby slightly crimped the edge portion of the paper and firmly hold the latter in its proper position on the negative.
- In witness whereof, I hereunto subscribe my name this 9th day of November, A. D. 1917.
- ALFRED E. KAISER.
